Fig 7

Fig 8

FIG. 1 is a perspective view of a programmed control unit for a plurality of projectors or the like, showing my new design, with the cover removed;

FIG. 2 is a top plan view thereof, without cover;

FIG. 3 is a front elevational view thereof, with the cover in place;

FIG. 4 is an end elevational view thereof seen from the left side of FIG. 3;

FIG. 5 is a rear elevational view thereof;

FIG. 6 is an end elevational view thereof;

FIG. 7 is a top plan view, similar to FIG. 2, but with the cover in place; and

FIG. 8 is a bottom plan view thereof.

I claim:

The ornamental design for a programmed control unit for a plurality of projectors or the like, substantially as shown and described.
